The ornamental design for a fire pit stand, as shown and described.

DESCRIPTION

This application is related to U.S. Design patent application Ser. No. 29/865,766, filed Aug. 11, 2022, entitled Fire Pit, the entire disclosure of which is hereby incorporated herein by reference.

This application is also related to U.S. patent application Ser. No. 17/886,239, filed Aug. 11, 2022, entitled Portable Stove With Folding Stand, the entire disclosure of which is hereby incorporated herein by reference.

FIG. 1 is a top perspective view of a fire pit stand showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a bottom perspective view thereof.

FIG. 9 is a view similar to FIG. 1 but with additional dashed broken lines; and,

FIG. 10 is a view similar to FIG. 2 but with additional dashed broken lines.

The equally-dashed broken lines shown in FIGS. 1-10 are included for the purpose of illustrating portions of the fire pit stand that form no part of the claimed design.

The dash-dot broken lines shown in FIGS. 1-5, 8, and 10 define the bounds of the claimed design and form no part thereof.

The additional equally-dashed broken lines shown in each of FIGS. 9-10, but not also shown in FIGS. 1-8, are included for the purpose of illustrating unclaimed environmental structure that forms no part of the claimed design.

The surface shadings and contour lines shown in FIGS. 1-10 represent the three-dimensional character and contour of the fire pit stand.
